(57) **CLAIM**

We claim the ornamental design for a cooler, as shown.

DESCRIPTION

FIG. 1 is a top front right side perspective view of a cooler showing our new design;

FIG. 2 is a front elevational view thereof;

FIG. 3 is a right side elevational view thereof (the left side is a mirror image of FIG. 3); and,

FIG. 4 is a top plan view thereof.

The broken line showing is for illustrative purposes only,
and forms no part of the claimed design.
